COMBINATION BOOK MATCH AND SAMPLE
OR ADVERTISING CARRIER

Lewis Lipowitz, Baltimore, Md.

Application October 26, 1937, Serial No. 171,122

2 Claims. (Cl. 206—29)

This invention relates to book matches with particular reference to the advertising aspects thereof.

The use of book matches as an advertising medium is extremely well known. In view of their cheapness and universal use book matches are customarily given away free with purchases of cigarettes, cigars, smoking tobacco or other commodities incident to smoking. Accordingly, it has become established practice for manufacturers, business houses and others to utilize the cover of the book matches as an advertising medium on which to print an advertising message or advertisement. The fact that this is such a widely accepted and approved form of advertising is evidenced by the great multitude of advertising book matches bearing every conceivable form of message now given away. By constant use the book match has become a standardized accepted product so that nearly all of the book matches given away today are of a standard form and dimensions.

A great many of the advertisements carried by book matches relate to candy products, confections, chewing gum, simple medicinal pills and tablets, and products of a like nature. It is also well known that the manufacturers of such products are continuously distributing samples of the same in vast quantities, to promote their sale to the general public. A great many of these products have a particular appeal to the smoker for an after-smoke purpose, and as their number is now legion they comprise a body of the public that such manufacturers are continuously striving to reach.

Accordingly, it is the prime purpose of this invention to utilize the book match as a carrier medium for a sample to be given away therewith, the object being to attach the sample to the book match to form a single unit-handled combination book match and sample, the sample being supported by a sample carrier constituting either a separate element or formed as an integral part of the sample package.

Another object of this invention relates to so forming the sample containing package that it may be readily attached to the book match without any change in the form, shape and dimensions thereof, and which will also allow ready detachment of the sample without injury to the book match proper.

A further object of the invention relates to the forming of the sample containing package so that it may be attached with the match strips

to the book match cover by the common form of wire staple now used.

A still further object of the invention relates to so forming the bases of the match strips either 5 separate or integral therewith as to provide a pocket therein adapted to receive a sample, and to cover the same by a cover similar to that used in the conventional book match, as well as providing in such cover and match strip bases a readily detachable portion to facilitate the 10 removal of the sample without destroying the match book proper.

Another object of the invention relates to the formation of a sample carrier or package adapted to be separately attached to a match strip in 15 the book match, and directly held thereby.

This invention also contemplates the use of 20 the sample carrier which basically is in the form of a flat strip of thin cardboard, as a means for carrying an advertising message. Thus it is usually the case that a book match given away by a storekeeper carries advertising matter of some manufacturer, there being nothing on the book match carrying the name or other identifying 25 data of the storekeeper. In order to provide a means whereby the storekeeper may readily attach to the book match a tag bearing his name, address, etc., it is accordingly another object of this invention to so form a sample carrier as to 30 constitute a readily attachable and detachable tag having printed thereon such identifying data, to be attached to said book match. It is to be understood that such tag may bear any desired 35 form of advertisement other than that as indicated.

Other objects and structural details will be apparent from the subjoined description taken in connection with the drawings forming a part of this specification and in which:

40 Figure 1 is a perspective view of one form of the invention, showing a sample carried by the book match cover and match strip base.

Figure 2 is a perspective view of the back 45 of the book match shown in Figure 1.

Figure 3 is a plan view of one of the match strips employed in the book match of Figure 1.

Figure 4 is a detail sectional view on an enlarged scale, taken on line 4—4; Figure 1.

Figure 5 is a perspective view of a modified 50 form of a sample carried by the book match cover and match strip base.

Figure 6 is a plan view of one of the match strips employed in the book match of Figure 6.

Figure 7 is a detail sectional view taken on 55 line 7—7, Figure 5.

Figure 8 is a perspective view of another modification of a sample carried by the book match cover and match strip base.

Figure 9 is a plan view of one of the match strips employed in the book match of Figure 8.

Figure 10 is a detail sectional view on an enlarged scale, taken on line 10—10, Figure 8.

Figure 11 is an end elevational view of another modification somewhat similar to that of Figure 8, showing a sample carried by the book match cover.

Figure 12 shows another constructional form of sample carrying book match wherein the sample is arranged on a carrier element removably fixed to the cover of the book match and extending beyond the top thereof.

Figure 13 is an end elevational view of the modification shown in Figure 12.

Figure 14 is a plan view of the carrier element of Figure 12.

Figure 15 is a modification based on the form shown in Figure 12 wherein the carrier element is permanently fixed with reference to the book match.

Figure 16 shows a book match having a modified form of carrier element removably fixed to the lower end thereof.

Figure 17 is an end elevational view of the book match and carrier element of Figure 16.

Figure 18 is a plan view of the carrier element of Figure 16.

Figure 19 is a plan view of a modified form of the carrier element shown in Figure 18.

Figure 20 shows a modification of a removable carrier element wherein the sample attached thereto is arranged at one side of the book match.

Figure 21 shows a carrier element similar in form to that shown in Figure 20 but permanently attached to the book match.

Figure 22 shows a still further modification of a carrier element removably attached to a portion of the matches of one of the match strips.

Figure 23 is a detail sectional view of the modification of Figure 22 taken on line 23—23; Figure 22.

Figure 24 is an additional modification similar to that of Figure 21 except that the sample carrier element is arranged wholly within the book match cover so that the sample carried thereby is within the same.

Referring to the drawings, the book match 10 shown in Figure 1 comprises a cover 11 and a pair of paper match strips 12 of conventional shape and size except that the base portions 13 thereof are increased in length beyond the usual conventional length for a purpose to be herein-after described. The cover 11 is formed in one piece of a relatively thin but stiff cardboard in the manner well known and shaped to provide a holding flap 14, a back 15, and a cover flap 16, the holding flap 14 extending over the base portions 13. A wire staple 18 driven through the holding flap 14, match strip bases 13 and back 15 permanently holds the same in assembled relation to form the book match 10. Each of the base portions 13 of the match strips 12 is provided with a re-entrant rectangular cut-out portion 17, and on the holding flap 14 there is provided a rectangular window opening 19 the side thereof nearest the bottom edge of the book match being formed to provide a tab 20 extending into the rectangular opening 19 as clearly shown in Figure 1. A transparent sheet 21 of tissue paper or Cellophane is placed on the underside of the holding flap 14 to cover the window opening 19.

Prior to the assembly of the book match, there is placed within the cut-out portion 17, a wrapped sample 22 of any desired candy, gum, pill or other article of manufacture, which with the match strips 12 are placed in position between the holding flap 14 and back 15 with the sample 22 in registry with the window opening 19, the whole being attached together in assembled relation by the staple 18. It is thus seen that the sample 22 is securely held in place and is readily visible through the transparent cover 21 of the window opening 19. To facilitate removal of the sample 22, there is provided on the holding flap 14 and back 15 a line of perforations 23 starting with the tab 20 and extending around the bottom edge of the book match and on the back 15 outlining the cut-out portion 17. Hence by merely pulling the tab 20 backwardly and rearwardly, the sample 22 is quickly and simply removed out of its pocket.

It is to be understood that while the cut-out portions 17 and window opening 19 are shown rectangular in form the same may assume any desired shape and size to accommodate any desired form of sample. Preferably the sample 22 should not exceed in thickness the combined thickness of the match strips 12 so that the bottom part of the book match 10 containing the sample will be flat as shown.

A modified book match construction for carrying a sample is shown in Figure 5. In this form the extended base portions 13a of the match strips 12a are each formed with a like circular opening 17a to receive therein a flat round sample 22a. The back 15a and holding flap 14a of the cover 11a are formed with a circular row of perforations 24. In the assembly of the parts the sample 22a is brought into registry with perforated circles 24 and said parts comprising the back 15a, match strips 12a and holding flap 14a being permanently fastened together by the staple 18. The sample 22a is thus securely contained within a pocket formed in the book match and may readily be removed by the simple expedient of pressing upon either of the circular portions 25 defined by the circular row of perforations 24 to sever the same from the holding flap 14a and back 15a in the manner readily apparent, thus forcing the sample 22a out of its pocket.

In the form shown in Figure 8, the extended base portions 13b of the match strips 12b are each provided with a like opening 17b shown rectangular in form, the side portions 28 of the base portion 13b on each side of the opening 17b having a transverse row of perforations 29 in alignment with the upper edge of the opening 17b, see Figure 9. Provided on the holding flap 14b and back 15b is a transverse row of perforations 30 and 31 lying in the same plane and spaced from the bottom edge of the book match a sufficient distance so that with the sample 22b placed in the openings 17b of the match strips 12b and the whole placed between the holding flap 14b and back 15b of the cover 11b, the perforations 29 on the base portions 13b and the perforations 30, 31 on the cover are in registry in the same place. In this position the parts are stapled together by the staple 18, with the sample 22b securely held in its pocket defined by the opening 17b, holding flap 14b and back 15b.

The perforations 29, 30 and 31 indicate tear lines along which the lower portion 32 of the book match may be torn in order to remove the sample 22b contained therein. It will be observed that in this form after the removal of the sam-

ple, the book match 10b will have the same appearance, form and shape as that of a book match of conventional form.

The form of book match and attached sample as shown in Figure 8 may be modified to the extent shown in Figure 11. In this instance, the match strips 12c are of conventional form with base portions 13c of conventional length as used in a standard book match. The cover 11c however is made identical with the cover 11b of Figure 8 as to the holding flap 14c, back 15c and cover flap 16c, the holding flap and back being also provided with the transverse row of perforations 30 and 31. Preferably the cover 11c and match strips 12c are initially assembled and fastened together by the staple 18, the base of the book match then providing a pocket 35 extending transversely of the same and open at each end. Within this pocket 35 there is inserted a sample 22c protected by a suitable wrapper, said sample being held within the pocket in any desired manner such as by glueing or pasting the sample wrapper to the inside of the cover forming the pocket, by stapling, or by glueing or pasting a band or wrapper around the outside of the pocket or base of the book match, so as to extend over the open ends of the pocket whereby to retain the sample in position. The sample 22c is removed from the book match by tearing the pocket portion thereof along the perforations 30, 31 in exactly the same manner as set forth above with reference to the sample carrier in the book match showing in Figure 8.

It will be appreciated that this manner of carrying a sample as shown in Figure 11 is particularly well adapted for samples that are thin and flat such for example as a stick of chewing gum, a razor blade, packets of powder, cosmetics or any other article of a like form, the length of which does not exceed the width of the book match. Again it will be noted that upon removal of the sample, the book match will have the same appearance, form and shape as that of a standard form of book match.

In each of the forms of sample carrying book match as shown in Figures 1, 5, 8 and 11 it will be observed that the sample is actually away from or to one side of the match strips proper so as to be in fact in external relation thereto. The sample thus does not interfere with the opening or closing of the cover flap nor with the removal of the matches, and furthermore cannot be affected by the chemicals forming the match heads.

Another method of providing a sample carrying structure to a book match is shown in Figures 12 to 23, inclusive.

Referring to Figure 12, 10 indicates generally a conventional standard form of book match containing a pair of match strips 12 and a one piece cover 11 providing a holding flap 14, a back 15 and a cover flap 16, the base portion 13 of the match strips being arranged between the holding flap 14 and back 15, all of which are attached together by the staple 18. Arranged between the inside match strip 12 and the inside of the back 15 of the cover is a carrier element or tag 40, shown in plan in Figure 14. The tag 40 is formed of a strip of thin relatively stiff cardboard similar to that used in the cover 11 and comprises a lower locking portion 41 and an upper carrier portion 42 separated by a transverse slot 43 the width of which is equal to the thickness of the cover 11 and having a length equal to the width of cover 11, for a purpose to be hereinafter described. The tag 40 is

preferably formed as to have its greatest width in the transverse region of the slot 43 to provide connecting portions 44 at each end of the slot, and the side edges 45 of the locking portion being inclined downwardly to the lower edge 46 thereof as shown. Adapted to be attached in any desired manner to the carrier portion 42 is a sample 47, the shape of the carrier portion 42 obviously being determined by the shape and size of the sample.

With the sample 47 attached to the tag 40, the same is assembled with the book match by the simple expedient of inserting the cover flap 16 through the slot 43 in such manner that the locking portion 41 will contact the inside surface of the cover 11. The tag 40 is then moved downwardly so that the sample 47 lies adjacent the hinged portion 11' of the cover, with said hinge portion in the slot 43, as clearly shown in Figures 12 and 13. In this position of the tag 40, the lower edge 46 of the locking portion 41 is forced between the base 13 of the inside match strip and the back 15 whereby the tag is positively retained in its proper position, see Figure 13, at all times. The removal of the sample 47 and tag 40 is achieved simply by opening the cover 16 and pulling the tag outwardly. The sample may also be removed by the tearing off of the carrier portion 42 at the connecting portions 44.

It is to be observed that the carrier portion 42 of the tag 40 need not necessarily carry a sample, as the space defined by said carrier portion both on the front and rear thereof is well suited to have printed thereon an advertising message for the purpose as set forth in the above objects of the invention. The tag 40 with the advertisement printed thereon is shown in Figure 14. As indicated both faces of the carrier portion may carry advertisements.

In the event it is desirable to permanently attach the tag 40 to the book match, see Figure 15, the locking portion 41a is made of a greater length than the locking portion 40 so that the lower edge 46a is in registry with the lower edge 45 of the match strips and is thus fastened therewith to the cover by the staple 18.

In the form of sample carrying book match shown in Figure 16, there is utilized a tag 50 made of the same material as the tag 40 which is provided with a transverse slot 51, a carrier portion 52, a locking portion 53 and connecting portions 54. Viewing Figure 18 the upper edge of the slot 51 is provided with a centrally disposed cut-out portion 55, the width and length of the slot 51 being such as to snugly receive therein the cover 11 of the book match, in the same manner as the slot 43 in the tag 40. Attached to the carrier portion 52, in any desired manner, is a sample 56, it being understood that the carrier portion may instead carry an advertisement on the face and back thereof in the manner as shown and described with reference to the tag 40, see Figure 14. The tag 50 is assembled with the book match by inserting the cover 11 thereof through the slot 51 in such a manner that the tag 50 will be placed between the inside match strip and the inside surface of the cover back 15; the tag 50 being then pulled downwardly so that the locking portion 53 will abut the base portions 13 of the inside match strip with the portion of the cover connecting the back 15 and holding flap 14 lying in the slot, see Figure 17. The dimensions of the cut-out portion 55 are such as to receive therein the staple 18,

see dotted line showing in Figure 16. This construction of the tag 50 is such as to provide both a simple, quick and effective assembly of the same with the book match to effect a positive attachment therewith. The sample 56 may be removed by a pulling of the tag 50 out of the book match or by tearing the tag at the connecting portions 54.

Should it be desired to permanently affix the tag 50 to the book match the same may be formed without the cut-out portion 55 and the locking portion 53 directly attached along with the match strips to the cover 11 by the staple 18.

Figure 19 shows a modification of the tag 50 wherein the tag 50a is formed with side flaps 57, and an end flap 58, and further provided with the scored or fold lines 59 whereby by a holding and pasting of the flaps to each other and with the edge portion 58a of the flap 58 pasted to the body of the tag adjacent the slot 51, will provide a completely closed container or box for the sample constituting an integral part of the tag 50a. A similar form of container construction may obviously be applied to the tag 40 and to the tags hereinafter described. The dotted line portion 55a indicates the cut-out portion which may be provided for the same purpose as set forth above with reference to the cut-out portion 55 of the tag 50.

In place of the sample there may be provided a plurality of sheets of advertising matter fastened in any desired manner to the tag sections.

The modification shown in Figure 20 consists in providing a flat thin sheet of cardboard of the same material as that used in the tags as above described to provide a tag 60, preferably rectangular in form having a width exceeding the width of the book match cover 11 and a length substantially equal to the length of the match strips. The lower edge 61 of the tag 60 is provided with a cut-out portion 62 to clear the staple 18 when the locking portion 63 shown in dotted lines of the tag 60 is inserted between the inside match strip and the back of the cover in the same manner as the tags 40 and 50 are positioned. The carrier portion 64 extending beyond one side of the book match may carry either a sample 65 or a printed advertisement in the manner indicated and as shown on the tag 40, Figure 14. The tag 60 when positioned in the book match is securely held therein both by the frictional engagement of the locking portion 63 between the base portion of the match strips and the back 15 of the cover as well as by the staple 18 fitted within the cut-out portion 62. Should it be desired to permanently affix the tag 60 to the book match there is provided a like tag 60a wherein the locking portion 63a is not formed with the cut-out portion 62 so that the staple 18 will pass through said locking portion 63a as clearly shown in Figure 21.

To remove the sample carrying tag 60 in the form shown in Figure 20 the same is simply moved or pulled outwardly lengthwise of between the match strips and cover, while in the form shown in Figure 21, the sample 65 is removed by tearing along the perforated line 66 provided on the tag 60a. Preferably the tear line 66 is so positioned on the tag 60a as to be inside of the book match cover which will serve as a reinforcement for the carrier portion 64a.

While in the various modifications of sample carrying or advertising tags as described above, each form of tag is shown associated with the

book match cover, it is also feasible to mount such a tag directly on the match strips to be solely carried thereby. Such a form of tag 70 is shown by way of example in Figures 22 and 23, 5 and is formed like the above mentioned tags of a like thin and relatively stiff cardboard to provide a carrier portion 71 and a locking portion 72 each of any suitable size and dimensions. The inside longitudinal edge of the locking portion 72 is provided with an integral reversely bent flap 73 which at its lower end terminates in a tab 74 that extends beyond the lower edge of the locking portion 72. In the assembly of the tag 70 to the book match, the tag 70 is first 10 placed over a certain number of match heads at one side of the inside match strip 12 with the locking portion 72 facing the back 15 and with the tab 74 of the flap 73 inserted between the rows of match heads. Then by a downward 15 movement of the tag 70, the certain number of matches at one side of the inside match strip becomes placed between the flap 73 and locking portion 72, as clearly shown in Figure 23, further downward movement of the tag 70 being continued until the tab 74 is forcibly inserted 20 between the base portions of the match strips, the tag 70 thereby assuming its final mounted position. Viewing Figure 23, it will be seen that sidewise movement of the tag 70 relative to the 25 match strip is prevented while movement of the tag outwardly lengthwise of the match strip is prevented both by the frictional engagement of the tab 74 with the match strip bases and by the cover 11. The flap 73 is hidden behind and is 30 held in position by the outside match strip 12. As with the preceding described forms of tags, either a sample 75 or an advertisement may be 35 respectively attached and printed on the carrier portion 71. The removal of the tag 70 is affected 40 by the simple expedient of pulling the same outwardly lengthwise of the match strips 12.

In the form of sample carrying book match shown in Figure 24, the tag 80 with sample attached is placed directly within the cover of the book match, the match strips 12d being of reduced width in order to accommodate the tag 80 within a book match cover 11 of conventional size. The tag 80 comprises a vertical carrier portion 81 and a lateral locking portion 82 which is adapted to overlap the base portion 13d of the match strips 12d, so that the staple 18 will fasten the tag along with the match strips to the cover 11, whereby the match strips 12d and the carrier portion 81 will lie in side by side relation. Attached to the carrier portion 81 is a sample 85, which may be detached from the book match by a tearing off of the carrier portion 81 in the manner readily apparent. In this constructional form the sample 85 is completely covered as well as protected by the book match cover.

It is desired that it be understood that in view of the various methods illustrated of applying a sample or advertising carrier to a book match that various combinations thereof may be effected by combining the features of one form with the features of another, and that numerous changes in the shape, size and formation of the various sample or advertising carriers may be resorted to within the spirit of the invention and scope of the appended claims.

Having thus set forth and disclosed the nature of this invention, what is claimed is:

1. In combination with a book match including at least one match strip, a cover and a staple

attaching said match strip at its base to said cover; a sample carrying or advertising tag having an intermediate portion of greater width than the width of said book match cover, a transverse slot in said intermediate portion, a cut-out portion formed centrally of said slot at one edge thereof, said book match cover extending through said slot in such relationship to said tag whereby the end portion of said tag to one side of said slot including said cut-out portion will be disposed between said match strip and the inside of said cover at the base of said match strip, said staple being disposed within said cut-out portion, the other end portion of said tag on the other side of said slot extending exteriorly of said book match and adapted to carry said sample or advertising.

2. In combination with a book match including at least one match strip, a cover and a staple attaching said match strip at its base to said cover; a sample carrying or advertising tag, a slot in said tag, a cut-out portion formed centrally of said slot at one edge thereof, said book match cover extending through said slot in such relationship to said tag whereby a portion of said tag to one side of said slot including 5 said cut-out portion will be disposed between said match strip and the inside of said cover at the base of said match strip, said staple being disposed within said cut-out portion, and another portion of said tag adapted to carry the sample 10 or advertising will extend exteriorly of said book match.

LEWIS LIPOWITZ.
